UNITED STATES PATENT OFFICE.

CARL AMEL LIND, OF MALDEN, ILLINOIS, ASSIGNOR OF ONE-FOURTH TO WILLIAM A. THORNTON AND ONE-FOURTH TO HARRY M. RICHARDS, BOTH OF GALESBURG, ILLINOIS.

LOCK FOR TIES, TIE-PLATES, RAILS, AND RAIL-ANCHORS.

1,137,153.

Specification of Letters Patent.

Patented Apr. 27, 1915.

Application filed November 17, 1913. Serial No. 801,513.

To all whom it may concern:

Be it known that I, CARL AMEL LIND, a citizen of the United States, residing at Malden, in the county of Bureau and State of Illinois, have invented a new and useful Lock for Ties, Tie-Plates, Rails, and Rail-Anchors, of which the following is a specification.

My invention relates to means for preventing railroad ties and rails from "creeping" or moving from their proper positions, which movements are caused both by the frictional contact of the rolling stock wheels with the rails and by the rails rebounding.

The principal object of the invention is to provide means securable to one or more ties and adapted to prevent more than a very slight movement of an anti-creeper or rail-anchor relatively to said tie or ties.

Another object is to provide means which holds said ties, anchor, and a rail-seat or tie-plate from more than a very slight movement relatively to each other.

With these and other objects in view, which objects will readily appear as the nature of the invention is more fully disclosed and better understood, the invention consists in the novel construction, combinations and arrangement of elements and parts thereof shown, described and claimed.

More specifically stated, and referring to the preferred structure shown in the accompanying drawings, it consists in a device attachable to a railway tie or the like, or to two or more adjacent ties, and adapted to prevent undue movement of a rail anchor relatively thereto, it being understood that the rail-anchor may be any one of a large number of such devices, and that the invention is by no means limited in its extent to any particular type or class thereof.

The type of anchor shown is that in which two members, one commonly known in the art as the "base" or "clip" and a co-acting member known as the "mate," frictionally grip the oppositely disposed rail-flanges or base, the interlocked portions of said members lying beneath said rail-base.

It may here be added that a tie-plate may be used or omitted in connection with my improvements, with equal facility and efficiency.

In said drawings, Figure 1 is a top plan, partly in section and partly broken away,

showing a preferred embodiment of my improvement as it appears when combined with a pair of adjacent parallel railway ties, tie plates, and rail; Fig. 2 is a bottom plan of the lock-bar alone, one of its ends broken off; Fig. 3, an end elevation, the lock-bar shown partly in section in the line 3—3 in Fig. 2; Fig. 4, a transverse section, the plane thereof taken in the line 4—4 in Fig. 1; Fig. 5, a similar view, taken in the line 5—5 in Fig. 1; Fig. 6, a front elevation of the lock-plate, its end portions broken away; and Fig. 7, a modification.

Coming now to a detailed description of the drawings and referring to each element and part thereof (where expedient) by a distinguishing numeral, 1, 1 designate a pair of ties; 2, 2, tie-plates or rail-seats; and 3, 3, the flanges of an ordinary railway rail, the ball omitted and the web 4 shown in section.

5 and 6 designate respectively the clip and mate members of a rail anchor shown and described in my co-pending application Serial No. 693,049, filed April 25, 1912. Any one of numerous rail anchors, consisting of either a one-piece anchor or an anchor having co-acting or interlocking parts, may be employed. In fact, the structural features of the parts briefly described and above designated by numerals concern my invention only in combinations therewith. The invention *per se* is shown best in Fig. 2 and comprises a bar or plate 7 having apertures 8 in its end portions.

10 designates a rib running along the outer edge of what, for the purposes of this specification I may term the rear end 9, and 11 indicates a similar rib on its other end, 12.

13, 14 designate a pair of rail engaging lugs or clips preferably beveled off at their inner edges. The body portion of the bar is curved upwardly at 15 to provide a pocket 16. 17 is a locking tongue or extension of the raised portion 15.

The rail, having been positioned on the ties, the anchor is then placed thereon with its jaws, gripping the edges of the rail-base flanges 3 and its projection 21 abutting the adjacent tie. If a tie-plate or rail-seat 2 be used, it also is positioned, and the rib 26 with which it is usually provided will lie against one of the ribs 10 or 11 of the lock-plate 7, and the co-acting wedge-faces of the ribs

of said plates will, when the spikes are driven, as will presently be described, force the vertical wall of said rib 26 into frictional contact with and against the edge of the flange 3 and thus aid in holding it from either longitudinal or lateral movements. The lock-bar 7 is then slidably turned into position, with one member of the anchor resting in the pocket 16, the end walls of which, together with the rail engaging lugs 13 and 14, afford shoulders 22 which prevent lateral movement to a greater extent than is desired—the amount being optional.

Spikes 27 are driven through the apertures in the lock-plate 7 and tie-plate 2 and into the tie or ties. Should it in certain cases be desired, one end portion of the plate 7 may be omitted, in which event it would terminate substantially at either of the places indicated by the broken lines *a—a* and *b, b*, Fig. 2, and in such case the spikes are driven through both holes 8 in the other end of the plate 7. However, the preferred manner of securing said plate is to drive the spikes through all the holes 8 shown, whereby it is rigidly secured to both ties 1 and said ties rigidly secured to each other thereby. The tie-plates are rigidly secured to the plate 7 by said spikes, and the rib 26 is thus held tightly against the edge of the rail base. The rail-anchor is secured to the rail in its usual manner, dependent upon its character, and the shoulders 22 prevent it from more than a minute movement relatively to the rail and ties. Thus it will be seen that the ties, tie-plates, rail, rail-anchor, and locking-plate are locked each to each of the others and that neither can move independently of another excepting the unimportant distances possibly permitted by reason of the spikes not snugly fitting their apertures or by reason of a rail-anchor not fitting snugly in the pocket 16.

In order to provide a frictional lock which will be effective in preventing movement of the rail-anchor without like movement of the locking-plate, I have provided the lip or tongue 17 which (inasmuch as said plate is preferably malleable iron) may be struck down into contact and frictional engagement with the rail, as shown clearly in Fig. 3. The elements will moreover cause a rust joint to form at their points of contact.

I have not deemed it necessary to encumber this specification and the accompanying drawings with descriptions of numerous modifications which have been contemplated by me. However, in order to illustrate modified means for securing or locking a rail anchor to a tie, I have shown in Fig. 7 a rail-anchor identical with the one elsewhere shown, but have provided the abutment 21 thereof with an opening which receives a bolt 35 which passes through a tie 1 and which is secured by a nut 36. This provides

a very simple means for locking the rail anchor to the tie.

Some of the advantages not hereinbefore recited may be summarily stated as follows:

The improvements are adapted for use on either double or single track roads.

The abutment 21 prevents movement of the anchor in one direction, but not in the other. It will be evident that my improvement prevents movement of the anchor in the opposite direction, caused generally by rebounding of the rail.

The locking plate is placed elsewhere than at the "joint-ties" and preferably at the midlength of one rail and opposite the joint of the parallel or other track rail. Inasmuch as the rail-flange is prevented by the locking-plate-ribs from lateral movement at the mid-length thereof—which is the usual place where a rail "spreads"—the device is an aid in preventing wrecks.

Buckling of the rail is to some extent at least prevented, for inasmuch as the locking-plate is secured to the ties, it will be effective in resisting buckling tendency, because its upper portion lies over the rail flange.

The word "lock" as employed herein is but relative, for there will be some minor movement of the parts; said word I therefore comprehend to mean and to be construed as meaning restraint.

The rail-anchor members may be considered as an unitary structure, complete in itself, and the plate which is securable to the ties and which retains said anchor from movement may be considered and designated as additional, independent, locking means.

Having thus set forth the preferred construction, the purposes and the advantages of my invention, I claim as new and desire to secure by Letters Patent the following, to-wit:

1. In combination, a railway rail, a tie to which it is secured, a rail-anchor comprising transversely interwedging members, and separate means securable to a tie and adapted to engage one of said interwedging members for preventing said rail-anchor from bodily lateral movement.

2. A rail-anchor lock having a pocket in which one end portion only of a rail-anchor is adapted to be seated, and a lip overhanging said pocket.

3. In combination with a railway tie and a railway rail, a rail-anchor clip, a rail-anchor mate adapted for transverse wedging engagement therewith, and a plate securable to said tie for locking said clip and thereby said mate relatively to the tie.

4. In combination, a railway rail, a plural member rail-anchor adapted to grip it, and means substantially embracing one member of said anchor to prevent lateral movement thereof.

5. In combination with a railway tie, a

- 5 rail thereon, a rail-anchor engaging said rail and adapted to abut said tie to restrain the anchor comprising interlocking members from movement theretoward as the rail tends to move in that direction, and means for restraining the anchor from movement in the opposite direction.
6. In combination with a rail-anchor and rail, a plate having shoulders adapted to prevent material movement of the anchor and having a portion adapted to be bent from its normal position and into contact with the rail.
7. The combination with a railway tie, a railway-track rail, and a rail-anchor, of a locking-plate adapted to be secured to said tie to prevent material movement of the anchor relatively thereto, and to thereby prevent substantial movement of the rail relatively to the tie, said plate having a portion adapted to be forced out of its normal position and into contact with said rail, whereby said plate frictionally binds said rail.
8. The combination with a railway tie and a railway track rail secured thereto, of a plural-piece rail-anchor and means embracing and holding one member of said anchor from material movement relatively to said tie and rail, the held member being adapted to engage and restrain its companion member from movement.
9. The combination with a railway rail and a rail-anchor, of means for preventing material movement of either with relation to the other, said means including a plate having a centrally arranged pocket adapted to receive one end of the anchor and having portions adapted to receive one edge of the rail flange.
10. In combination, a railway tie; a rail secured thereon; a rail-anchor clip adapted to engage one flange of said rail; a rail-anchor mate adapted for sliding engagement with said clip and to grasp the other flange of said rail; and means embracing said clip and thereby restraining said mate and rail from material movement relatively to said tie.
11. In combination, a railway tie; a rail secured thereon; a rail-anchor clip adapted to engage one flange of said rail; a rail-anchor mate adapted for engagement with said clip and to engage the other flange of said rail; and locking means secured to said tie and having a pocket adapted to receive said clip.
12. A device of the character described consisting of an elongated bar having a rib on its lower surface, at the outer portion thereof, and having a rail-engaging lug at the inner end of said rib, and having a pocket adjacent said lug.
13. A device of the character described consisting of an elongated bar having a pair of rail-engaging lugs intermediate its ends and having a pocket disposed between said lugs, said pocket adapted to receive a portion of a rail-anchor.
14. A device of the character described consisting of an elongated bar securable to a railway tie and provided with a pocket provided in part by opposed walls and in part by a transversely arranged tongue.
15. In a device of the character described, and in combination, a railway-tie, a railway rail, means for securing said rail on said tie; a rail-anchor member adapted to engage one side of the rail base, a rail-anchor member adapted to engage the opposite side of the rail base, said members being interwedged, and a fixed element adapted to restrain one of said rail-anchor members from movement relatively to the tie.

In testimony whereof I hereunto affix my signature this eighth day of November, 1913.

CARL AMEL LIND.
